UNITED STATES PATENT OFFICE.

FRANK CARL STIEFEL, OF PHILADELPHIA, PENNSYLVANIA, ASSIGNOR TO THE CURTIS PUBLISHING COMPANY, OF PHILADELPHIA, PENNSYLVANIA, A CORPORATION OF PENNSYLVANIA.

TOWEL-RACK.

1,141,664.

Specification of Letters Patent.

Patented June 1, 1915.

Application filed June 27, 1914. Serial No. 847,609.

To all whom it may concern:

Be it known that I, FRANK C. STIEFEL, a citizen of the United States, and a resident of Philadelphia, in the county of Philadelphia and State of Pennsylvania, have invented certain new and useful Improvements in Towel-Racks, of which the following is a specification.

Individual towels are frequently provided and in many places are required and it is less expensive and more desirable to provide textile towels and wash them than it is to provide paper or like towels. However, in providing textile towels it is desirable to have them free for unlimited use, yet incapable of being diverted from their intended use or carried away and mislaid or lost.

The principal object of the present invention is to provide a comparatively simple, inexpensive and reliable towel rack or fixture by means of which textile towels can be used in the manner above indicated but without fear of their being lost or taken away or diverted from their intended use.

The invention will be claimed at the end hereof, but will be first described in connection with the embodiment of it illustrated in the accompanying drawings, in which—

Figure 1, is a perspective view illustrating a towel rack or holder embodying features of the invention. Fig. 2, is an enlarged view of the lower portion of the device. Fig. 3, is an enlarged view, principally in section, of a portion of the upper part of the device, and Fig. 4, is a front view, partly in section, illustrating a detail.

In the drawings 1 and 2 are a pair of straight rigid pins, of which one, 2, is tubular. These pins are shown as projecting from a panel or the like 3, that may be appropriately secured to the wall above a wash basin 5.

6, is a lock mounted on the panel 3 and secured to the tubular pin 2. This lock may be of the spring variety and is provided with the usual key-hole 7 and other fittings of a lock. The bolt 8 of this lock is normally projected by the spring 9 through a suitable opening in the hollow pin 2 into its interior.

10, is a button headed screw or the like, arranged below the tubular pin 2 with its head projecting. For example, it can be in-

serted into the wall 12 in such a way that it is fixed and immovable, while its head is at 55 some distance from the wall.

13, is a rod provided at one end with a plate 4, Fig. 2, having an opening or button-hole or key-hole slot 15. The opening or key-hole slot 15 is in part appropriate for 60 the passage of the head of the pin 10 and in part appropriate for the reception of the shank of the pin 10. This button-hole or key-hole slot in connection with the pin constitutes a detachable connection or support for the lower end of the rod. The other end of the rod 13 is provided with a head 16, formed with a neck or notch 17. The upper end of the rod 13 is angularly bent for insertion into the socket 2 and the 70 head 16 is adapted to act upon the beveled end of the bolt 8 and so push it back in order that it may enter the neck or notch 17 and so hold the rod in the socket. A key 18 is provided for retracting the bolt 8 and 75 freeing the rod 13. The lower end of the rod 13 is offset as at 19 so as to guide the soiled towels *a* into the basket *b* and at its lower end it is provided with the button-hole or key-hole slot 15, as has been stated. 80

In use a supply of towels each having an appropriate opening, gromet or loop, is placed upon the pins 1 and 2 by passing the latter through the openings, gromets or loops. The feather 20 on the pin 1, operates 85 to prevent the towels from improperly slipping over the pin 1 or from slipping over it more than one at a time. Of course, when the towels are applied to the pins the upper end of the rod 13 is withdrawn from the 90 tubular pin 2, which is easily accomplished by operating the key 18 to turn the lock so as to retract the bolt 8. After the supply of towels is in place, the rod 13 is applied by securing one of its ends by the button 95 and button-hole connection 10 and 15 and the other of its ends by the bolt 8. Thereafter any one desiring to do so can use the towels, one at a time and as many as desirable, by simply freeing them from the pin 100 1 and letting them slide down the rod 13. The latter, however, prevents the towels from being taken away or improperly used. After use, the towels are permitted to slide along the rod 13, which guides them into 105 the basket or receptacle *b*. The towels can

be removed for washing by freeing the rod 13 in the manner described, and stripping them from it.

The provision of two pins and the rod 5 forming a continuation of one of them presents the towels in convenient form to be taken one at a time and used; for all that the user has to do is to pull a towel off the pin 1 and it is easy to get one towel and 10 to then let it slide off the pin 2 and along the rod 3, when it is in convenient position for use.

What I claim is:

1. A device of the class described comprising the combination of a pair of straight rigid immovable pins in parallel relation and of which one is tubular, a spring lock of which the bolt is projectible into and retractile from the tubular pin, a button below the tubular pin, and a rod provided at one end with a plate having a key-hole slot

for the button and at the other end with a head and a notch adapted to coöperate with the spring bolt, substantially as described.

2. A device of the class specified comprising the combination of a rod having a straight pin portion, terminal connections for immovably holding the rod, and a straight immovable pin parallel with said pin portion, whereby a group of clean towels in flat relation hangs solely from the two pin portions and whereby each towel is conveniently presented and may be used even for the face while secured by one corner to the rod, substantially as described.

In testimony whereof I have hereunto signed my name.

FRANK CARL STIEFEL.
